CLAIM

The ornamental design for a handset telephone, as shown and described herein.

DESCRIPTION

FIG. 1 is a front, top and right side perspective view of a handset telephone showing my new design;

FIGS. 2 and 3 are respectively top and bottom plan views thereof;

FIGS. 4 and 5 are respectively front and rear elevational views thereof;

FIG. 6 is a right side elevational view thereof, the side opposite being substantially a mirror image thereof;

FIG. 7 is a right side elevational view of a second embodiment thereof, the side opposite being substantially a mirror image;

FIG. 8 is a bottom plan view of the second embodiment; the sole difference of this embodiment, vis-a-vis the first embodiment showing, being the small, substantially flat, pad attached upon the shoe sole as manifested in FIGS. 7 and 8.

The showing in abbreviated form of cord in all figures has been for ease and clarity of illustration.
